UNITED STATES PATENT OFFICE.

FREDERICK B. KIRKNESS, OF YORKLYN, DELAWARE, ASSIGNOR OF ONE-HALF TO
FREDERICK BIDDLE KIRKNESS, OF WILMINGTON, DELAWARE.

WINDOW SCREEN.

Application filed October 16, 1922. Serial No. 594,842.

To all whom it may concern:

Be it known that I, FREDERICK B. KIRKNESS, a citizen of the United States, residing at Yorklyn, in the county of New Castle and State of Delaware, have invented certain new and useful Improvements in Window Screens; and I do declare the following to be a full, clear, and exact description of the invention, such as will 10 enable others skilled in the art to which it appertains to make and use the same.

My invention has for its object to provide an improved form of window screen frame of such construction that different portions 15 of the upper and lower side bars may be angled with respect to each other when inserting or removing the frame, means being provided however for holding said side bars in rectilinear form when the screen 20 is in place.

A further aim is to obtain the desired results simply by forming saw cuts in opposite sides of the upper and lower side bars of the frame, to permit the portions of 25 the bars at opposite sides of the cuts to be angled.

With the foregoing in view, the invention resides in the novel subject matter herein-after described and claimed, the description 30 being supplemented by the accompanying drawings.

Figure 1 is a side elevation of a screen constructed in accordance with my invention.

Figure 2 is an upper edge view of the screen in place within a window frame.

Figure 3 is a duplicate of Fig. 2 with the exception that it illustrates the manner of angling the upper and lower side bars when 40 inserting or removing the screen.

Figure 4 is an enlarged upper edge view of the upper frame bar.

In the drawings above briefly described, the numeral 1 designates a rectangular 45 screen frame adapted to be received between the usual sash guiding strips 2 of a window frame and to occupy any desired portion

of said frame. The top and bottom bars 3 and 4 of the frame 1, in the form of construction here illustrated, are cut preferably 50 near one end, so that each of said bars may be converted into an angular form as shown in Fig. 3, when inserting or removing the screen. This is preferably accomplished by providing an outer saw cut 5 in each of 55 the bars 3 and 4 and two saw cuts in the inner sides of said bars, jointly forming a V-shaped cut 6, the cut 5 of each bar being opposite the apex of the V-shaped cut, permitting angling of the top and bottom 60 bars of the screen as seen in Fig. 3, during which movement the screen wire 7 forms a hinge.

After the screen is in place and the bars have again been moved into rectilinear form, they may be held in this form by any preferred means. On account of simplicity however I have shown sliding wire bolts 8 engaged with screw eyes 9 and extending 70 across the cuts 6.

From the foregoing, it will be seen that I provide an extremely simple screen frame construction for permitting very easy installation and removal, the arrangement being advantageous over screen frames of 75 the types now commonly used. As excellent results have been obtained from the details disclosed, they are preferably followed, but within the scope of the invention as claimed, numerous minor changes may be made. 80

I claim:

A window screen having the top and bottom bars of its frame formed with transverse cuts, each of said bars having a V-shaped cut in one side, and a single saw 85 cut in its other side opposite the apex of the V whereby the portions of said bars at opposite sides of said cuts may be angled when inserting the frame, and means for holding said bars in rectilinear form when 90 the frame is in place.

In testimony whereof I have hereunto affixed my signature.

FREDERICK B. KIRKNESS.
